UNITED STATES PATENT OFFICE.

LEO E. BOWKER AND DANIEL F. BOWKER, OF WINCHESTER, NEW HAMPSHIRE, ASSIGNEES TO THE ASHUELOT CAN COMPANY, OF SAME PLACE.

DESIGN FOR A HEAD FOR OIL-CANS.

SPECIFICATION forming part of Design No. 17,038, dated December 28, 1886.

Application filed November 4, 1886. Serial No. 218,023. Term of patent 7 years.

To all whom it may concern:

Be it known that we, LEO E. BOWKER and DANIEL F. BOWKER, citizens of the United States, residing at Winchester, in the county of Cheshire and State of New Hampshire, have invented and produced a new and original Design for the Heads of Oil-Cans; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Figure 1 is a perspective view of an oil-can, showing the external appearance of my newly-designed head for the same. Fig. 2 is a sectional view showing its sharp peripheral edge and vertical shoulder.

The leading feature of my design consists in a circular head having a raised or convex surface sloping from its central portion to the edge of the outer rim of the can at *t*, so that the exterior surface of the head extends over

and above the rim, presenting to the eye a uniform rounded surface which is very attractive in its general appearance. The under side of the head consists of a circular base or projection, *h*, having a vertical edge around its circumference. This base or projection rests within the inside rim of the can. The convex or upper portion of the head extends over the side or edge of the base *h*, terminating in a sharp edge at its circumference at *t*, as shown in Fig. 2.

We claim—

The design for the head of a can herein shown and described, the same having a sharp peripheral edge and vertical shoulder and a convex exterior surface, substantially as set forth.

In testimony whereof we affix our signatures in presence of two witnesses.

LEO E. BOWKER.

DANIEL F. BOWKER.
